AIRPLANE LAUNCHING APPLIANCE

Filed July 12, 1928

Inventor,
Leslie R. McDonald.

By his Attorney
Ames Wilson.

UNITED STATES PATENT OFFICE

LESLIE R. McDONALD, OF MONTREAL, QUEBEC, CANADA

AIRPLANE-LAUNCHING APPLIANCE

Application filed July 12, 1928. Serial No. 292,113.

My invention relates to that class of airplane launching appliances wherein the airplane is suspended and is made to develop sufficient speed to sustain it in flight before being released from the means by which it is suspended; and objects of my improvements are to utilize the force of gravitation in developing a take-off speed in the suspended airplane; to utilize certain novel forms of suspending and releasing means, both manually and automatically controlled, and to so sustain the airplane that it may be drawn back and allowed to swing downward and forward toward the take-off point and to be released before the speed developed has been materially diminished by any upward swing of the suspending apparatus or the airplane. These features of my invention will be more fully explained and pointed out herein-after.

In the drawings Fig. 1 is an elevation of one form of my improved take-off apparatus, showing an airplane suspended thereby; Fig. 2 is a view of the same looking to the left on Fig. 1; Fig. 3 is a view of the same showing the airplane sling and airplane drawn back to an elevated position, and ready for release; Fig. 4 is a view on an enlarged scale of the sling basket and part of the fuselage of the airplane, looked at from the same position as shown in Fig. 2, part of the basket and of the fuselage being broken away for clearness; Fig. 5 is a plan view of the same, omitting the fuselage; and Fig. 6 is a detail of the airplane carrying loop on the basket.

Similar letters of reference designate similar parts in all the figures.

Two towers, 1, 2, preferably of steel construction, support a girder 3, from which suitable cables 4, 5, 6, 7, are stretched to and secured to the corners of the basket 8, which is of sufficient strength and rigidity to carry the weight of an airplane and to support it in proper taking off position. This basket is shown as being made of angle iron, reinforced by diagonal braces 9, 10, and provided with a downwardly extending rest 11 and with a carrying loop 12, preferably braced by a small cable 13 extending from it to the basket. At the rear of the basket is mounted a releasing

mechanism which is shown as consisting of a catch 14 pivoted at 15 to the frame work of the basket and having a counterbalance weight 16 sufficiently heavy to normally throw the hook of the catch up.

Below the catch 14 a keeper 17 is pivoted at 18 to the frame of the basket, and is also provided with a counterbalance weight 19 sufficiently heavy normally to throw the opposite end of the keeper up. A check rope 20 is fastened to the end of the keeper 17 and extends down to the fuselage of the airplane where it can be reached by the pilot; or it may be extended to a point free of the airplane if it is desired that the catch shall be released by someone not in the airplane. From the girder 3 a cable 21 is stretched to the top of a post 22, and from this cable is suspended a sheave 23 over which runs a cable 24, which also runs over a sheave 25, near the top of the pole 22, and thence down to the drum 26 of a hoisting engine 27 mounted near the foot of the pole. This hoisting engine may be of any approved type. So I consider it unnecessary to illustrate the details of its construction.

The other, or free, end of the cable 24 is provided with a loop 25 which is adapted to receive the free end of the catch 14 as illustrated in Figs. 4 and 5. When the loop 25 is fastened to the catch 14, the basket 8, with an airplane attached, may be swung backward and upward as illustrated in Fig. 3 by winding the cable 24 around the drum 26 of the engine 27, and when the check rope 20 is pulled downward, the keeper 25 will release the catch 14, allowing it to slip out of the loop 25 so that the basket 8 and the airplane may swing downward and forward in the position shown in Fig. 2.

In or on the fuselage of the airplane 43 is mounted a carrying device which consists essentially of a hook 30 pivoted as at 31 to a frame element 32 attached to the fuselage of the airplane. This hook 30 is counterbalanced by a weight 33, so that the point normally rises.

A keeper 34 is also pivoted to the framework as at 35 and is extended into an arm 36. Normally the keeper tilts upward so as to en-

gage its arm 37 outside of the hook 30, and thus prevents the hook from rising.

To one end of the keeper element is fastened a check rope 38, which passes down into the fuselage and is carried to a position where it can be reached by the pilot or other person desiring to release the airplane.

From the arm 36 another check rope 39 extends to a sheave 40 and then downward toward the foot of the pole and is fastened to a suitable cleat 41 mounted on the pole 22. The length of this check rope 39 and its adjustment is such that when the airplane has reached the take-off position in its downward and outward swing, for instance, as shown in Fig. 2, the check rope 39 will become taut between the arm 36 and the cleat 41, and the continued swing of the basket 8 and airplane will cause the keeper 34 to be sprung free of the hook 30 by the drag on the check rope 39, and the increased drag on the rope will separate the members of a conventional bell cord coupling 44, so that one end of the rope will remain attached to the arm 36, while the other end will remain attached to the pole. When the hook 30 is released by the keeper 34, it will free itself from the loop 12 and thus free the airplane from the basket, this being accompanied by separation of the bell cord coupling 44 as the airplane continues its forward movement, as already pointed out.

This check rope 39, as will be seen, is in the nature of a safety line which will automatically release the airplane from the sling basket in case the pilot should omit to do so. However, this safety check rope 39 may be disconnected, if desired, or it may be operated by hand from the ground or by automatic means.

To give stability to the airplane in its connection with the sling basket 8 I provide a suitable stop 42 secured to the framework of the fuselage, and adapted to cooperate with the rest 11 so as to prevent the tail of the airplane from dropping down, out of proper position in its relation to the basket 8, the airplane being preferably balanced so that there is a slight inclination of the tail to drop when the airplane is suspended from the basket 8.

In order to raise the airplane to a position where it will swing free of the ground, suitable elevating means are provided, such as an elevator 45, which is indicated as having its platform 46 substantially level with the surface of the ground. The airplane may be rolled upon the platform and then raised by the elevator to a position where proper connection can be made with the sling basket 8, after which the elevator can be lowered away from the plane. As the mechanism of this elevator may be of any approved pattern, and as I do not claim novelty in the details of the construction of the elevator, it is unnecessary

to describe the details of this mechanism, but I have indicated a platform elevator having a piston 47 below the head 48 of which compressed air or the like may be forced by any suitable means to raise the platform elevator. 70

In practice, an airplane is mounted upon the elevator platform and raised so that the hook 30 may be passed through the loop 12 and held in position by the keeper 34, and the elevator is then lowered away from the airplane. The catch 14 is passed through the loop 25 and locked in position by the keeper 17. The sling basket 8, carrying the airplane, is then drawn backward and upward toward the sheave 23 by the hoisting engine 27 rolling up the cable 24 on its drum 26. The airplane is then in position for launching. Its engine may then be started. When satisfactory speed has been developed, the pilot may pull the check rope 20, thus freeing the catch 14 from the loop 25 and allowing the sling basket and the airplane to swing downward and forward, its movement being accelerated by the pull of the propeller. This pull of the propeller, aided by the swinging movement under the force of gravitation, will, if the apparatus has been properly proportioned, develop sufficient speed when the airplane is passing the lowest point of its swing to enable it to support itself in flight. At this instant the pilot may pull the check rope 38, thus freeing the catch 30 and releasing the airplane from the sling basket 8, or release may be effected automatically through the check rope 39 operating as above described. The airplane, being thus freed from the sling basket, proceeds on its flight while the sling basket will gradually swing back to its former position above the elevator. 95

I desire it to be understood that the particular means which I have illustrated and described for suspending and releasing the airplane may be modified, as by the use of mechanical equivalents, without departing from the spirit of my invention, for it is obvious that the release of the carrying means and hoisting means might be accomplished through mechanical apparatus instead of hand controlled apparatus, and various other modifications might be made. 105

Having thus described my invention, what I claim and desire to secure by Letters Patent of the United States is:—

1. In an airplane launching apparatus, the combination of optionally releasable swinging means for suspending the airplane, releasable hoisting means for swinging the suspending means backward and upward, means for releasing the hoisting means, and means for releasing the airplane from the suspending means. 120

2. In an airplane launching apparatus, the combination of optionally releasable swinging means for suspending the airplane, means 130

for elevating the airplane to connect with the swinging means, releasable hoisting means for swinging the suspending means backward and upward, means for releasing the hoisting means, and means for releasing the airplane from the suspending means.

3. In an airplane launching apparatus, the combination of optionally releasable swinging means embodying cables sustaining a unitary element for suspending the airplane, releasable hoisting means for swinging the suspending means backward and upward, means for releasing the hoisting means, and means for releasing the airplane from the suspending means.

4. In an airplane launching apparatus, the combination of optionally releasable swinging means for suspending the airplane, releasable hoisting means for swinging the suspending means backward and upward, releasing means extending from the airplane to the releasable means, means for releasing the hoisting means, and means for releasing the airplane from the suspending means.

5. In an airplane launching apparatus, the combination of optionally releasable swinging means for suspending the airplane, releasable hoisting means for swinging the suspending means backward and upward, means for releasing the hoisting means, and means operable from the airplane for releasing the airplane from the suspending means.

6. In an airplane launching apparatus, the combination of optionally releasable swinging means for suspending the airplane, releasable hoisting means for swinging the suspending means backward and upward, means for releasing the hoisting means, and automatic means for releasing the airplane from the suspending means.

7. In an airplane launching apparatus, the combination of a pair of towers, a carrying member connecting the towers, cable suspended from the carrying member, an airplane carrying element supported by the cables, releasable connecting means between the carrying element and the airplane, means for elevating an airplane to connect with the carrying element, hoisting means embracing a cable, a windlass and means for turning the windlass to hoist the carrying element and airplane backward and upward, and means for releasing the airplane from the hoisting means to permit the forward swing of the airplane.

8. In an airplane launching apparatus, the combination of a pair of towers, a carrying member connecting the towers, cables suspended from the carrying member, an airplane carrying element supported by the cables, releasable connecting means between the carrying element and the airplane, means for elevating an airplane to connect with the carrying element, hoisting means embracing a pole, a cable connecting the pole and the car-

rying member, a sheave carried by the cable, a sheave carried by the pole, another cable running through the sheaves, a windlass and means for turning the windlass to hoist the carrying element and airplane backward and upward, and means for releasing the airplane from the hoisting means to permit the forward swing of the airplane.
